ELECTRIC RANGE

Leo F. Berg, Oak Park, Ill., assignor to Hotpoint
Inc., a corporation of New York

Application February 6, 1948, Serial No. 6,631

5 Claims. (Cl. 219—37)

1

The present invention relates to electric ranges, and more particularly to such ranges provided with tilting backsplash structure.

An electric range is normally provided with a cooking top carrying backsplash structure adjacent to the rear thereof, which backsplash structure carries instrument and heating control equipment on the front thereof. It is now proposed to increase considerably the normal height of the backsplash structure in order to extend its usefulness and to achieve a better balance in design. However, this proposal would normally necessitate a larger shipping crate for the range and the consequent increase in transportation costs. Also most modern kitchens are provided with built-in overhead cabinet structure rendering it impossible to adjust or repair the equipment carried by the front of the backsplash structure from the front of the range after the range has been installed without removing it from its normal position adjacent to a wall of the kitchen when high backsplash structure is carried by the rear of the cooking top.

Accordingly, it is a general object of the present invention to provide in an electric range, high backsplash structure that does not complicate shipping of the range and that permits ready adjustment and repair of the equipment carried by the front of the backsplash structure after installation of the range.

Another object of the invention is to provide in an electric range, folding backsplash structure; whereby the over-all height of the range may be substantially reduced in order that the range may be conveniently crated and shipped.

Another object of the invention is to provide in an electric range, forwardly folding backsplash structure, whereby the equipment carried by the front of the backsplash structure may be rendered readily accessible from the front of the range to permit adjustment and repair thereof.

A further object of the invention is to provide in an electric range including a cooking top and a backsplash panel, mechanism for mounting the backsplash panel for tilting movement with respect to the cooking top between a substantially upright normal position and a forwardly folded operated position.

A further object of the invention is to provide in an electric range of the character noted, improved hinge mechanism for mounting the backsplash panel for tilting movement with respect to the cooking top and improved latch mechanism for controlling the position of the backsplash panel.

2

A further object of the invention is to provide in an electric range of the character noted, electrical wiring and control facility accommodating the movements of the backsplash panel.

- 5 A still further object of the invention is to provide in an electric range of the character noted, electrical power interlock facility controlled in accordance with the position of the backsplash panel.
- 10 Further features of the invention pertain to the particular arrangement of the elements of the electric range, whereby the above-outlined and additional operating features thereof are attained.
- 15 The invention, both as to its organization and method of operation, together with further objects and advantages thereof, will best be understood by reference to the following specification taken in connection with the accompanying
- 20 drawings, in which Figure 1 is a fragmentary front view of the upper portion of an electric range embodying the present invention; Fig. 2 is an enlarged fragmentary transverse sectional view of the upper portion of the electric range, taken along the line 2—2 in Fig. 1, illustrating the latched position of latch mechanism incorporated therein; Fig. 3 is an enlarged fragmentary transverse sectional view of the upper portion of the electric range, taken along the line
- 25 3—3 in Fig. 1, similar to Fig. 2, illustrating the unlatched position of the latch mechanism; Fig. 4 is an enlarged fragmentary side view of the upper portion of the electric range shown in Fig. 1, illustrating the normal position of hinge
- 30 mechanism incorporated therein; Fig. 5 is an enlarged fragmentary side view of the upper portion of the electric range shown in Fig. 1, similar to Fig. 4, illustrating the operated position of the hinge mechanism; Fig. 6 is an enlarged fragmentary front sectional view of the right-hand upper portion of the electric range, taken along the line 6—6 in Fig. 4, further illustrating the details of the latch and hinge mechanisms; and
- 35 Fig. 7 is an enlarged fragmentary rear perspective view of the upper portion of the electric range shown in Fig. 1, illustrating the arrangement of the electrical wiring incorporated therein.

Referring now to the drawings, the electric range 10 there illustrated, and embodying the features of the present invention, comprises an upstanding frame or body 11 provided with a substantially horizontally disposed cooking top 12 terminating adjacent to the rear thereof in an upwardly directed pedestal 13 carrying up-

wardly extending backsplash structure 14. The body 11 comprises an oven disposed in the right-hand upper portion thereof below the cooking top 12 and having an open front closed by a suitable door 15, the door 15 being hinged adjacent to the lower edge thereof in a manner not shown and provided with an operating handle 16 positioned adjacent to the upper edge thereof just below the cooking top 12. Also the body 11 comprises a storage space disposed in the left-hand upper portion thereof below the cooking top 12 and receiving a sliding drawer having a front cover 17 that is provided with an operating handle 18 positioned adjacent to the upper edge thereof just below the cooking top 12.

The cooking top 12 merges with the top of the body 11 and terminates adjacent to the rear thereof in the pedestal 13 as previously noted, which pedestal 13 is of hollow construction. Also the cooking top 12 has a plurality of openings formed in the left-hand surface thereof in which corresponding surface heating units are removably secured in place. Specifically, the left-hand surface of the cooking top 12 has four openings formed therein arranged both front and rear and left and right, and removably carrying corresponding surface heating units. For convenience the four surface heating units will be referred to hereinafter as the left front, the right front, the left rear and the right rear surface heating units. In passing it is noted that the left rear surface heating unit may also be lowered below the cooking top 12 in order to provide a deep-well cooking unit. In the drawings, the removable left front and right front surface heating units are respectively illustrated at 19 and 20, the left rear and right rear surface heating units being hidden by other structure. Also the oven comprises the usual bake and broil heating elements, not shown.

The backsplash structure 14 is of hollow construction and constitutes an instrument and heating control equipment panel, as well as a lamp support arranged to illuminate the cooking top 12. Specifically, the right-hand portion of the backsplash structure 14 carries the instrument and heating control equipment while the left-hand portion thereof has an opening 21 formed therein in which there is arranged an upwardly and rearwardly sloping light reflector 22, the upper left-hand portion of the backsplash structure 14 constituting a light shade or hood 23 carrying a removable, elongated electric lamp 24. Accordingly, the electric lamp 24 when illuminated throws light upon the curved reflector 22, whereby the cooking top 12 is adequately illuminated for cooking purposes. Of course, the backsplash structure 14 also serves the purpose of preventing food cooking in receptacles arranged on the surface heating units from splashing upon the wall of the kitchen in which the electric range 10 is disposed; whereas the upper right-hand portion of the cooking top 12 also serves as a work platform in the preparation and serving of food.

Specifically, the right-hand front surface of the backsplash structure 14 has six openings formed therein and arranged in a lower row and two additional openings formed therein and arranged in an upper row. Four control switches 25, 26, 27 and 28 are respectively arranged in the first four of the lower openings from the left toward the right and respectively control the electric circuits of the left front, the left rear, the right rear and the right front surface heat-

ing units. An oven temperature regulator 29 is arranged in the fifth lower opening; and a fifth control switch 30 is arranged in the sixth lower opening and controls the electric circuits of the oven. A timing mechanism 31 is arranged in the left-hand opening and controls the opening and the closing of the electric circuits to the oven in accordance with predetermined times; and a timing alarm mechanism 32 is arranged in the right-hand upper opening. This disposition of the instrument and control equipment upon the right-hand front of the backsplash structure 14 provides for ready control of the four surface heating units, as well as the oven.

15 The backsplash structure 14 is mounted upon the pedestal 13 for tilting movement with respect to the cooking top 12 by an arrangement including two hinge mechanisms 40 and 50 respectively disposed on the left-hand side and on the right-hand side of the range 10 and positioned mutually within the hollow pedestal 13 and the hollow backsplash structure 14. More particularly, the backsplash structure 14 is mounted by the hinge mechanisms 40 and 50 for tilting movement between a substantially upright normal position, as illustrated in Figs. 1 and 4, and a forwardly folded operated position as illustrated in Figs. 5 and 7. When the backsplash structure 14 is moved to its forwardly folded operated position, disposed over the cooking top 12, the over-all height of the range 10 is considerably reduced with respect to the normal height thereof established with the backsplash structure 14 in its substantially upright normal position. This arrangement is very advantageous as the over-all height of the range 10 for crating purposes incident to shipping may be considerably reduced even though the backsplash structure 14 has a height considerably greater than that normally employed in conventional electric ranges. Accordingly, in the range 10 a high backsplash structure 14 has been provided that is capable of being folded for crating purposes so that the over-all height of the range 10 is equivalent to that of conventional ranges having low backsplash structures.

Preferably the hinge mechanisms 40 and 50 are identical; and, as best shown in Figs. 4 and 5, the hinge mechanism 50 comprises a stationary section 51, a movable section 52 and a guide link 53. The hinge section 51 terminates in a fixture 54 provided with top and front flanges 55 and 56 respectively suitably secured to the adjacent top and front walls of the pedestal 13. Also the hinge section 51 has an elongated arcuate shaped guide slot 57 formed therein. The hinge section 52 terminates in a fixture 58 provided with bottom and front flanges 59 and 60 respectively suitably secured to the adjacent bottom and front walls of the backsplash structure 14. Also the hinge section 52 is provided with an arm 61 having an opening formed therein into which a pin 62 is arranged, the pin 62 being positioned in the guide slot 57 formed in the hinge section 51. The guide link 53 is substantially C-shaped, the upper and lower ends thereof being pivotally connected to two pins 63 and 64 respectively rigidly secured to the fixtures 58 and 54.

When the backsplash structure 14 occupies its substantial upright normal position as illustrated in Fig. 4, the bottom wall of the backsplash structure 14 is arranged in superimposed relation with respect to the top wall of the pedestal 13; the hinge section 52 terminating in the fixture 58 rigidly secured to the backsplash structure

14 occupies its fully downwardly projected position with respect to the hinge section 51; and the guide link 53 occupies its substantially upright position. At this time the pin 62 carried on the outer end of the arm 61 formed on the hinge section 52 is disposed in the lower end of the guide slot 57 formed in the hinge section 51; and the pivot pins 63 and 64 are positioned in substantial vertical alignment. The backsplash structure 14 may be moved from its substantial upright normal position to its forwardly folded operated position by pulling forwardly thereon with respect to the cooking top 12. At this time the pin 62 carried by the arm 61 formed on the hinge section 52 rides upwardly in the guide slot 57 formed in the hinge section 51; whereby the backsplash structure 14 is moved forwardly with respect to the pedestal 13 as it is tilted or rotated in the counterclockwise direction as viewed in Figs. 4 and 5. Accordingly, the guide link 53 is rotated in the counterclockwise direction about the pivot pin 64 as the backsplash structure 14 is moved to its forwardly tilted operated position causing the pivot pins 63 and 64 to move out of substantial vertical alignment. When the backsplash structure 14 is moved into its final forwardly tilted operated position as illustrated in Fig. 5, the pin 62 carried by the arm 61 formed on the hinge section 52 engages the upper end of the guide slot 57 formed in the hinge section 51, thereby positively limiting further tilting of the backsplash structure 14 toward the cooking top 12. This stop arrangement incorporated in the hinge mechanism 50 positively prevents the instrument and heating control equipment 25, etc., carried on the front of the backsplash structure 14 from striking the adjacent surface of the cooking top 12. At this time the pivot pin 63 disposed at the upper end of the guide link 53 is forwardly offset with respect to the pivot pin 64, since the backsplash panel structure 14 is moved substantially forwardly with respect to the pedestal 13 as it is rotated in the counterclockwise direction as viewed in Figs. 4 and 5. Accordingly, it will be understood that the hinge mechanism 50 is of the compound type imparting both forward shifting movement and rotative movement to the backsplash structure 14 when the backsplash structure 14 is moved from its substantially upright normal position to its forwardly folded operated position, and conversely, imparting both rearward shifting movement and rotative movement to the backsplash structure 14 when the backsplash structure 14 is moved from its forwardly folded operated position back into its substantial upright normal position. This compound hinge arrangement positively prevents the front lower edge of the backsplash structure 14 from binding on the front upper edge of the pedestal 13 or undesirable scraping of these adjacent parts over each other incident to tilting movement of the backsplash structure 14.

In view of the above description of the hinge mechanism 50 it will be understood that the hinge mechanism 40 is identical and comprises corresponding elements 41, 42 and 43; the hinge section 41 being rigidly secured to the pedestal 13, the hinge section 42 being rigidly secured to the backsplash structure 14, and the guide link 43 being pivoted between the hinge sections 41 and 42 in the manner described; all for the purpose previously explained.

Further the range 10 comprises latch mechanism 10 including a transversely extending latch

bar 71 carried by the rear wall of the pedestal 13 just below the top wall thereof. More particularly, the latch bar 71 is substantially C-shaped in cross section and is mounted for sliding movement on the rear wall of the pedestal 13 between a normal latched position illustrated in Fig. 2 and an operated unlatched position illustrated in Fig. 3 by an arrangement including two bolts 72 disposed on opposite sides of the rear wall of the pedestal 13. More particularly, the bolts 72 extend through cooperating openings formed in the rear wall of the pedestal 13 and thence respectively through two elongated slots 73 formed in the opposite ends of the latch bar 71 and receive cooperating nuts 74. The latch bar 71 includes a forwardly projecting flange 75 having a downwardly turned edge 76 that is provided with two spaced-apart notches or openings 77 and 78 formed therein respectively adjacent to the hinge mechanisms 40 and 50. More particularly, the notch 77 is disposed adjacent to a cooperating rearwardly projecting shoulder 42a formed on the hinge section 42, incorporated in the hinge mechanism 40; and the notch 78 is disposed adjacent to a cooperating rearwardly projecting shoulder 52a formed on the hinge section 52, incorporated in the hinge mechanism 50. When the latch mechanism 76 occupies its normal latched position as illustrated in Fig. 2, the notches 77 and 78 formed in the flange 75 of the latch bar 71 are respectively disposed out of alignment and to the left of the cooperating shoulders 42a and 52a respectively formed on the hinge sections 42 and 52. Also at this time the adjacent portions of the downwardly turned edge 76 provided on the flange 75 of the latch bar 71 are positioned over the associating shoulders 42a and 52a respectively formed on the hinge sections 42 and 52; whereby the latch bar 71 cooperates with the hinge mechanisms 40 and 50 positively to prevent movement of the backsplash structure 14 from its substantially upright normal position as shown in Fig. 4 to its forwardly tilted operated position as shown in Fig. 5. When the latch bar 71 is slid from the left toward the right from its latched position as shown in Fig. 2 to its unlatched position as shown in Fig. 3, the notches 77 and 78 formed in the flange 75 of the latch bar 71 are moved into respective alignment with respect to the shoulders 42a and 52a respectively formed on the hinge sections 42 and 52. Accordingly, at this time when the latch bar 71 occupies its unlatched position as shown in Fig. 3, the backsplash structure 14 may be moved from its substantially upright normal position illustrated in Fig. 4 to its forwardly folded operated position illustrated in Fig. 5, since the shoulders 42a and 52a respectively formed on the hinge sections 42 and 52 may ride through the respective cooperating notches 77 and 78 formed in the flange 75 of the latch bar 71.

In order to control the position of the latch bar 71 an arrangement is provided that includes a handle 79 pivotally mounted by a screw 80 upon the rearwall of the body 11. More particularly, the screw 80 extends through an opening formed in the rear wall of the body 11 adjacent to the upper edge thereof and just below the pedestal 13 and thence through an opening formed in the handle 79, the outer end of the screw 80 receiving a cooperating nut 81. The screw 80 is arranged to the left of the vertical center line of the range 10 below and substantially in alignment with the center line of the right rear surface heating unit. Finally the upper end of the

handle 79 projects through a cooperating slot 82 formed in a lower flange 83 carried by the latch bar 71; while the lower end of the handle 79 terminates in a forwardly projecting hand-grasp 84. The latch mechanism 70 normally occupies its latched position illustrated in Figs. 2 and 4 and when it is desired to operate it to its unlatched position illustrated in Figs. 3 and 5, the serviceman removes the right rear surface heating unit from the cooperating opening formed in the cooking top 12. At this time the serviceman may reach through the right rear opening formed in the cooking top 12 and seize the hand-grasp 84. When the hand-grasp 84 is then moved toward the left from its normal position as illustrated in Fig. 2 to its operated position as illustrated in Fig. 3, the handle 79 is pivoted in the clockwise direction about the screw 80, whereby the latch bar 71 is moved toward the right from its latched position shown in Fig. 2 to its unlatched position shown in Fig. 3. After the latch mechanism 70 has thus been operated to its unlatched position with respect to the hinge mechanisms 40 and 50, the backsplash structure 14 may be operated in either direction with respect to the pedestal 13 in the manner previously explained.

As best shown in Figs. 4 and 7, the top of the body 11 terminates in inwardly directed marginal flanges 91, and the bottom of the cooking top 12 and the pedestal 13 terminate in inwardly directed flanges 92, the cooperating flanges 91 and 92 being suitably secured together in order to retain the cooking top 12 and the pedestal 13 in position on the top of the body 11. Likewise, the top of the pedestal 13 terminates in inwardly directed flanges 93, and the bottom of the backsplash structure 14 terminates in inwardly directed flanges 94, the flanges 93 and 94 being arranged to cooperate with each other when the backsplash structure 14 occupies its substantially upright normal position. Since the lower flanges 94 carried by the bottom of the backsplash structure 14 are spaced vertically a short distance above the upper flanges 93 carried by the top of the pedestal 13 by the hinge mechanisms 40 and 50, a trim 95 is secured to the lower surfaces of the flanges 94; whereby the trim 95 is positioned between the cooperating flanges 93 and 94 when the backsplash structure 14 occupies its substantially upright normal position, thereby to conceal the gap between the backsplash structure 14 and the pedestal 13.

The rear of the pedestal 13 is open and is normally closed by a removable lower cover 96 secured in place at the opposite ends thereof to the cooperating flanges 93 by a plurality of screws 97. Likewise, the rear of the backsplash structure 14 is open and is normally closed by a removable upper cover 98 secured in place about the marginal edge thereof to the cooperating flanges 94 by a plurality of screws 99. Accordingly, the hollow pedestal 13 and the hollow backsplash structure 14 respectively comprise top and bottom walls provided with connecting openings formed therein. Moreover, the interior of the hollow pedestal 13 is rendered readily accessible when the lower cover 96 is removed; and likewise, the interior of the hollow backsplash structure 14 is rendered readily accessible when the upper cover 98 is removed.

Also the range 10 comprises a power panel 100 carried by the body 11 and accessible through an opening 101 formed in the rear wall thereof; which power panel 100 comprises three terminals

102, 103 and 104 that are respectively connected by suitable wiring to the positive, neutral and negative wires of a conventional three-wire Edison source of current supply. Normally an A. C. source of current supply is utilized wherein the line to line voltage is approximately 220 volts and the line to neutral voltage is approximately 110 volts. Further, the range 10 comprises a master circuit controller 105 that is removably secured by two screws 106 to a substantially L-shaped bracket 107 that, in turn, is suitably secured to the lower surface of the flange 91 provided on the top of the rear wall of the body 11 adjacent to the right-hand side thereof and spaced toward the left from the associated hinge mechanism 50. The master circuit controller 105 is provided with a rocking control arm 108 arranged to cooperate with the movable hinge section 52 of the hinge mechanism 50. More particularly, when the backsplash structure 14 is moved to its substantially upright normal position, the lower end of the hinge section 52 engages an upturned end provided on the arm 108 depressing it and moving the master controller 105 to its closed circuit position. On the other hand, when the backsplash structure 14 is moved to its forwardly folded operated position, the lower end of the hinge section 52 disengages the upturned end of the arm 108 relieving it, permitting it to rise, moving the master controller 105 to its open circuit position.

The two line terminals 102 and 104 provided on the power panel 100 are connected by two wires 109 and 110 to two inlet terminals carried by the master controller 105; while two outlet terminals carried by the master controller 105 are connected directly to two flexible bus wires 111 and 112; and the neutral terminal 103 provided on the power panel 100 is connected directly to a flexible bus wire 113. Accordingly, when the master controller 105 occupies its closed circuit position, the wires 109 and 110 are respectively connected to the bus wires 111 and 112; and when the master controller 105 occupies its open circuit position the wires 109 and 110 are respectively disconnected from the bus wires 111 and 112. Accordingly, the master controller 105 constitutes a power interlock governed in accordance with the position of the backsplash structure 14; whereby the power from the power panel 100 is automatically disconnected from the bus wires 111 and 112, when the backsplash structure 14 is moved out of its substantially upright normal position. In passing, it is noted that the neutral terminal 103 on the power panel 100 is normally connected to ground potential and is, in turn, normally grounded to the metallic structure of the body 11.

The bus wires 111, 112 and 113 extend in multiple to the control switches 25, 26, 27, 28 and 30. The electric circuit from the left front control switch 25 is returned via three flexible conductors, indicated as a group at 114, to the left front surface heating unit; the electric circuit from the left rear control switch 26 is returned via three flexible conductors, indicated as a group at 115, to the left rear surface heating unit; the electric circuits from the right rear and the right front control switches 27 and 28 respectively are returned by two groups of flexible conductors, not shown, to the respective right rear and right front surface heating units; and the electric circuit from the oven control switch 30 is returned by four flexible conductors, indicated as a group at 116, to the oven

heating elements. Also, the electric circuit for the oven heating elements includes the oven temperature regulator 29 and the oven timing mechanism 31. Accordingly, the flexible bus wires 111, 112 and 113, as well as the groups of flexible conductors 114, 115, 116, etc., accommodate tilting movement of the backsplash structure 14 with respect to the pedestal 13. Further, it is noted that the oven temperature regulator 25 is operatively thermally associated with the oven by an arrangement including a fluid conduit 117 having a helical coil 117a incorporated therein in order to accommodate the tilting movement of the backsplash structure 14. Specifically, the lower end of the fluid conduit 117 terminates in a bulb, not shown, operatively associated with the oven structure, and the upper end of the fluid conduit 117 connects with a pressure chamber, not shown, formed in the oven temperature regulator 29. Finally, it is noted that the electric lamp 24 is provided with an electric circuit, including the bus wires 111 and 113, as well as a control switch, not shown; and likewise, the timing mechanism 31 includes an electrical operating motor, not shown, provided with an electric circuit, including the bus wires 111 and 113.

Accordingly, it will be understood that the cooking top 12 is commensurate with the top of the body 11, and is of one-piece construction, the downwardly turned front flange of the cooking top 12 integrally joining the downwardly turned end flanges thereof and the end flanges of the cooking top 12 integrally joining and merging into the rearwardly turned end flanges of the pedestal 13. Also the backsplash panel 14 is of one-piece construction, the rearwardly turned top flange of the backsplash 14 integrally joining the rearwardly turned end flanges thereof. The width of the backsplash panel 14 between the end flanges thereof is commensurate with the width of the pedestal 13 between the end flanges thereof, so that when the backsplash panel 14 occupies its normal position the end flanges thereof complement the end flanges of the pedestal 13.

In view of the foregoing description of the construction and arrangement of the tilting backsplash structure 14, it will be understood that, after the range 10 has been installed in a kitchen, the electrical wiring arranged in the hollow pedestal 13 and in the hollow backsplash structure 14, as well as the instrument and circuit control switches 25, etc., carried by the front of the backsplash structure 14, are readily accessible from the front of the range 10 for adjustment and repair; all without moving the range 10 from its installed position in the kitchen. In order to accomplish this end, the repairman merely removes the right rear surface heating unit, operates the handle 79, and then moves the backsplash structure 14 to its forwardly folded operated position disposed over the cooking top 12. At this time the cover 98 may be removed from the rear of the backsplash structure 14 merely by removing the screws 99; whereby the interior of the electrical wiring arranged in the hollow backsplash structure 14, as well as the terminals and other mechanical portions of the instrument and circuit control switches 25, etc., are readily accessible from the front of the range 10.

In view of the foregoing, it is apparent that there has been provided an electric range incorporating tilting backsplash structure accom-

modating compact crating and shipping of the range, as well as ready adjustment and repair of the instrument and circuit control equipment carried thereby after installation of the range.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In an electric range including a body, a cooking top substantially commensurate with the top of said body and carried thereby, said cooking top terminating adjacent to the rear thereof in an upwardly directed pedestal, said cooking top having downwardly projecting front and end flanges, said pedestal having rearwardly projecting end flanges merging with said end flanges of said cooking top, backsplash structure arranged on said pedestal, said backsplash structure having rearwardly projecting top and end flanges, instrument and heating control equipment carried on the front of said backsplash structure, and a pair of spaced-apart hinge mechanisms respectively secured to said cooking top and to said backsplash structure for mounting said backsplash structure for tilting movement with respect to said cooking top between a substantially upright normal position and a forwardly folded operated position, said end flanges of said backsplash structure complementing said end flanges of said pedestal when said backsplash structure occupies its normal position; the combination comprising compound links incorporated in said hinge mechanisms for shifting said backsplash structure bodily forwardly away from said pedestal as said backsplash structure is tilted forwardly into its operated position, stops incorporated in said hinge mechanisms for positively limiting tilting movement of said backsplash structure beyond its operated position so as to prevent said instrument and heating control equipment from striking said cooking top when said backsplash structure occupies its operated position, and ready releasable means for restraining said backsplash structure in its normal position.
2. In an electric range including a cooking top, backsplash structure arranged adjacent to the rear of said cooking top, and a pair of spaced-apart hinge mechanisms respectively secured to said cooking top and to said backsplash structure for mounting said backsplash structure for tilting movement with respect to said cooking top between a substantially upright normal position and a forwardly folded operated position; the combination comprising a latch member carried by said cooking top and movable between latch and unlatch positions, said latch member being disposed below said backsplash structure when said backsplash structure occupies its normal position, at least one of said hinge mechanisms carrying an abutment cooperating with said latch member, said latch member respectively engaging and disengaging said abutment in its latch and unlatch positions in order respectively to latch and unlatch said backsplash structure in its normal position and to release said backsplash structure for tilting movement from its normal position into its operated position, and manually operable means for selectively operating said latch member between its latch and unlatch positions.

3. In an electric range including a cooking top, backsplash structure arranged adjacent to the rear of said cooking top, said cooking top having an opening therein disposed forwardly with respect to said backsplash structure, a heating unit removably arranged in said opening, and a pair of spaced-apart hinge mechanisms respectively secured to said cooking top and to said backsplash structure for mounting said backsplash structure for tilting movement with respect to said cooking top between a substantially upright normal position and a forwardly folded operated position; the combination comprising a latch member carried by said cooking top and movable between latch and unlatch positions, said latch member being disposed below said backsplash structure when said backsplash structure occupies its normal position, at least one of said hinge mechanisms carrying an abutment cooperating with said latch member, said latch member respectively engaging and disengaging said abutment in its latch and unlatch positions in order respectively to latch said backsplash structure in its normal position and to release said backsplash structure for tilting movement from its normal position into its operated position, and means including a manually operable handle disposed below said cooking top and accessible through said opening when said heating unit is removed therefrom for selectively operating said latch member between its latch and unlatch positions.

4. In an electric range including a cooking top supporting surface heating units, backsplash structure arranged adjacent to the rear of said cooking top and carrying on the front thereof circuit control switches, first electric circuit connections between said surface heating units and said circuit control switches, power terminals, second electric circuit connections between said circuit control switches and said power terminals, and a pair of spaced-apart hinge mechanisms respectively secured to said cooking top and to

said backsplash structure for mounting said backsplash structure for tilting movement with respect to said cooking top between a substantially upright normal position and a forwardly folded operated position, said first and second electric circuit connections being flexible to accommodate the tilting movement of said backsplash structure between its normal and operated positions; the combination comprising a master switch arranged in said second electric circuit connections and operative between open and closed positions, and means cooperating with one of said hinge mechanisms and responsive to movement thereof incident to movement of said backsplash structure into its normal and operated positions for respectively operating said master switch into its closed and open positions.

5. The combination in an electric range as set forth in claim 2, wherein at least one of said hinge mechanisms also incorporates cooperating stops for positively limiting tilting movement of said backsplash structure so as to prevent said backsplash structure from striking said cooking top when said backsplash structure occupies its operated position.
